Primary Examiner — Marissa J Cash(74) *Attorney, Agent, or Firm* — Muncy, Geissler, Olds & Lowe, P.C.(57) **CLAIM**

The ornamental design for a quadcopter toy, as shown and described.

DESCRIPTION

FIG. 1 is a Perspective view of a quadcopter toy showing my new design;

FIG. 2 is a Front elevational view thereof;

FIG. 3 is a Rear elevational view thereof;

FIG. 4 is a Left side view thereof;

FIG. 5 is a Right side view thereof;

FIG. 6 is a Top plan view thereof; and,

FIG. 7 is a Bottom plan view thereof.

Broken lines immediately adjacent claimed surfaces represent boundaries of the claim and form no part thereof; all other broken lines depict unclaimed environmental subject matter and form no part of the claims.

1 Claim, 7 Drawing Sheets(56)
